UNITED STATES PATENT OFFICE.

CHAUNCEY BLAIR FORWARD, OF URBANA, OHIO.

STEAM SUPERHEATER.

Application filed January 3, 1919. Serial No. 269,425.

To all whom it may concern:

Be it known that CHAUNCEY BLAIR FORWARD, a citizen of the United States, residing at Urbana, in the county of Champaign 5 and State of Ohio, has invented certain new and useful Improvements in Steam Superheaters, of which the following is a specification.

My invention relates to an improvement 10 in steam superheaters, and the improvement resides more particularly in a new and novel super-heating unit having a longitudinally corrugated body constructed to withstand intense heat and high internal pressures 15 without distortion and collapse.

In the accompanying drawings, Fig. 1 is 20 a cross section of a portion of a furnace or boiler embodying my invention, and Fig. 2 is a plan view thereof and section on line 2—2, Fig. 1. Fig. 3 is a side elevation of 25 super-heating pipe section constructed according to my invention. Fig. 4 is an enlarged perspective view of one end of said section.

25 In practicing processes of refining oil involving the use of super-heated steam, I have utilized steam super-heating coils placed within the throat of a combustion chamber of a furnace where the coils of 30 pipe are subjected to an intense heat from the fire. To withstand this heat for long periods I have encased portions of the pipe in protecting shells. Such protection is not 35 new broadly, but of the various modes of protection afforded as known to me none have been found entirely satisfactory by me until the present invention was developed.

As shown, this invention comprises a 40 straight pipe section 2 which is adapted to be joined to other pipe sections by elbow fittings or expandible loops 3' to form a super-heating coil. This coil may be placed in a separate steam super-heating furnace or mounted as an auxiliary heater within the 45 furnace walls of a steam boiler. In the present instance I show a boiler 4 of the Sterling type with a steam super-heating coil mounted therein at a point immediately above the fire chamber 5 and preferably in 50 the throat 6 adjacent the fire arch 7 and immediately beneath the inclined boiler tubes 8. Any number of pipe sections in the coil may be used dependent upon the degree of temperature desired and the relative location 55 of the super-heating coils, and the

placement of the coil in the throat 6 may be changed according to the requirements and the particular type of furnace involved. In any case, however, the pipe sections that are exposed to the direct flames must withstand an intense heat, and I therefore provide sections of pipe 2, with cast metal shells 3 of special construction and design so as to reinforce the pipes as well as to provide the pipes with an additional body of metal 60 adapted to heat up to a high degree for steam super-heating purposes. Each shell 3 is corrugated longitudinally, that is the body of the shell is provided with longitudinal ribs 9 and grooves 10 on opposite 65 sides thereof, and is further provided with a longitudinal rib 11 projecting upwardly from its upper flat face 12 centrally in line with the pipe 2 and of a greater height midway than at the ends of the shell. The 70 bottom face 13 of the shell is also corrugated or provided with a longitudinal rib 14 on the center line thereof, and this bottom rib may be the same as or of less height or depth than the top rib 11. Ribs 11 and 14 are 75 80 moreover of less length than the body of the shell, while the end portions of the shell are flat top and bottom so that they may be securely seated in the brick walls 4 of the furnace and prevented from turning and 85 being displaced. Such shell ends facilitate the building of the wall and the setting of the shells, and the pipe may be inserted into the shells with a tight fit or the shell cast on the pipe. In practise I prefer to cast the 90 shell directly upon the straight pipe section 2 leaving a predetermined length of pipe end 95 extending beyond each end of the shell. Thus in installing the pipe sections in a furnace, the shell sections are loosely seated 100 within the walls of the furnace to permit expansion, and the pipe ends extend through the wall and the elbow fittings or loops are connected outside of the wall to adjacent parallel pipes of the coil.

All of the pipe sections of the coil may 105 embody shells as described, but in practise I find that only those exposed to the most intense heat require such protection. Each pipe and shell is a unit which may be embodied in a coil or used in any suitable combination in a superheater. As I have used these units I find it a distinct advantage to employ a single cast shell extending the full width of the furnace and to have the ends 110

thereof seated for expansible movement within the walls of the furnace, and to avoid sagging, distortion or collapse of the pipe and shell I find it quite essential to have the 5 longitudinal ribs on the shell as described. Moreover, these ribs serve as heat-transmitting elements as well as strengthening elements and permit the body of the shell to be made thinner than if the shell were plain. 10 The adjacent longitudinal ribs of parallel shells are spaced apart more or less irregularly in the bank of pipe sections which make up the coil, and the vertical ribs on the shells may thus be utilized as baffle elements 15 in addition to strengthening elements. The top rib 11 is also in a more protected position from the flame than the bottom of the shell.

In summary, each superheating unit as described is adapted to withstand an intense 20 heat and high internal pressure while serving effectively to transmit the heat to the pipe to super-heat the steam passing therethrough, and one or more such units may be 25 used in any type or kind of boiler or furnace where an intense heat is generated and

high temperatures of steam or super-heating of steam is desired.

What I claim is:

1. A steam superheating unit, comprising 30 a pipe having a cast metal shell, cast full length in contact therewith provided with flat-seating surfaces at its opposite ends, and said pipe extending straight beyond said ends.

2. A furnace having opposite walls, in combination with steam superheating pipes having cast metal shells in close contact the full length thereof provided with flat extremities seated within said walls and ribbed 40 longitudinally between said extremities, and the opposite ends of said pipes being extended beyond the ends of said shells and projected outside of said walls, and expansible loops connecting the ends of adjacent 45 pipes and providing a continuous superheating coil.

Signed at Cleveland, in the county of Cuyahoga, and State of Ohio, this 19th day of December, 1918.

CHAUNCEY BLAIR FORWARD.
